FIRE HOSE CONNECTER HEAD

Filed Feb. 16, 1928

INVENTOR

Conrad J. Diez.

BY
Albert Dietrich
ATTORNEY

UNITED STATES PATENT OFFICE

CONRAD J. DIEZ, OF BALTIMORE, MARYLAND, ASSIGNOR TO AMERICAN BRASS & FIRE EQUIPMENT CORPORATION, OF BALTIMORE, MARYLAND, A CORPORATION OF MARYLAND

FIRE-HOSE CONNECTER HEAD

Application filed February 16, 1928. Serial No. 254,780.

The invention has for its object to provide a simple and compact connector head which may be carried by the pumping apparatus and have connected thereto a nozzle equipped 5 discharge hose line, and suction and pressure supply lines for connection with the pumping apparatus, suitable manually and automatically actuatable valves being provided in said head and all being arranged whereby the 10 head may be connected to a fire plug and a stream at service pressure played on the fire before and while the pumping apparatus connections are made, to be supplanted by a pressure stream through the same line after the 15 pumper connections have been made without the necessity of cutting of the stream flow at any time during the making of the said connections.

In its more detailed nature the invention 20 seeks to provide a connector head embodying certain new and useful improvements over the connector head disclosed in Patent Number 1,351,781 issued September 7, 1920, whereby a more simple and compact structure is 25 provided including simplified valve structures, one adapted to be hand manipulated and one automatically actuated to control the lower pressure stream distribution and the change to pressure stream distribution with- 30 out break of flow or loss of pressure below service pressure at any time.

Other objects will in part be obvious and in part be pointed out hereinafter.

To the attainment of the aforesaid objects 35 and ends, my invention consists in the novel details of construction, combination and arrangement of parts, all of which will be first fully described in the following detailed description, then be particularly pointed out in 40 the appended claim, reference being had to the accompanying drawings, in which:—

Figure 1 is a plan view illustrating the invention in use for supplying water to the 45 hose nozzle at hydrant or ordinary service pressure.

Figure 2 is a diagrammatic plan view illustrating the invention in use for supplying water to the hose nozzle at pumped pressure.

Figure 3 is a horizontal section illustrat-

ing the position of the valves for effecting the use disclosed in Figure 1.

Figure 4 is a horizontal section illustrating the position of the valves for effecting the use disclosed in Figure 2. 55

Figure 5 is a plan view of the invention per se.

Figure 6 is a vertical cross section taken on the line 6—6 on Figure 5. 60

In the drawing I have diagrammatically illustrated a fire hydrant and the same is indicated at 1, the large outlet thereof being indicated at 2.

The connector head which forms the subject matter of my present invention is preferably carried by the fire apparatus with the nozzle-equipped discharge hose line and pipe lines for connection with the suction or intake connection to the pumper and a pipe line for distributing water under pressure from the said pumper attached thereto. The nozzle-equipped discharge hose line is indicated at 3 and the same has provision at 4 for connection to the head. The suction line is indicated at 5 and has provision at 6 for connection to the head and at 8 for connection with the pumper, and the pressure distributor line is indicated at 9 and has provision at 10 for connection to the head and as at 11 for connection to the pumper. In Figure 1 of the drawing I have indicated the connector head attached to the fire hydrant and adjusted to play a stream of water on the fire at service pressure. In Figure 2 of the drawing I have diagrammatically indicated the connector head attached to the pumper and adjusted for supplying a stream under pressure provided by the said pumper. 65 70 75 80 85

In the practical development of the invention I provide a connector head casing 12 having a main valve chamber 13 which is cylindrical in shape and is accessible through a removable cap 14. The casing includes an inlet throat 15 having provision at 16 for connection to the outlet 2 of the fire hydrant. 90 95

A sector plate valve 17 is operable in the chamber 13, the said valve plate being removably mortise and tenon connected at 18 to an operating cradle 19, the trunnions 20 of 100

which have bearings in glands 21 provided in the casing cover and bottom.

One of the trunnions 20 is projected beyond its gland bearing and is fitted with an operating handle 22 formed to provide a pointer 23 at one end to indicate at all times the position of the plate valve in the chamber 13.

The chamber 13 communicates, through a passage 24, with a Y extension 25, one branch of the said Y having provision at 26 for connection with the hose line 3 and the other such branch having provision at 27 for connection with the pressure line 9 from the pumper.

15 A valve seat 28 is provided across the passage communicating with the pipe line 9 and a valve seat 29 is provided across the passage 24, the said seats being so arranged as to be controlled by a single flap valve 30 pivoted at 31 in the Y extension between the valve seats, and which said valve is adapted to alternately and automatically seat on the respective valve seats in a manner and for a purpose soon to be described.

25 The casing 12 is also provided with an outlet 32 adapted to communicate with the suction line 5 to the bumper, see Figure 7.

In use the connector head with the hose lines 3, 5 and 9 attached thereto is preferably carried by the fire apparatus with the plate valve 17 thereof adjusted to the position shown in Figures 1, 3, 5 and 6. As the apparatus reaches the fire hydrant it drops the connector head and the attached lines making the necessary run to lay the line 3. The connector head is then attached to the hydrant as indicated in Figure 1 of the drawing and it is only necessary to open the valve of the hydrant to play a stream onto the fire through the hose line 3 at hydrant service pressure, and the said stream continues to play on the fire until it has been possible to return the fire apparatus and make the necessary connections as indicated in Figure 2 of the drawing.

When the lines 5 and 9 have been connected to the pumper in the manner illustrated in Figure 2 the valve 17 is shifted from the position illustrated in Figures 1 and 3 to the position shown in Figures 2 and 4. When this shift is first occasioned water will pass through the outlet 32 into the suction line 5 but will continue to flow at service pressure through the passage 24 so as not to discontinue the supply of a stream to the fire through the hose line 3 at service pressure. When the pressure in the line 9 has been built up by the pumper above the pressure of the water passing through the passageway 24 the flap valve 30 will be automatically shifted from the position illustrated in Figure 3 to the position illustrated in Figure 4 when a stream at high pressure will supplant the service pressure stream in the hose line 3.

35 From the foregoing description it will be

observed that it is possible to play a stream of water on the fire at service pressure during the interval necessary to connect and bring into function the pumper and also possible to supplant that stream by a high pressure stream from the pumper without any "cut off" interval or any interval of "pressure reduction" below the service pressure of the fire hydrant. It will also be observed that it is only necessary to shift one valve, i. e., the rotary valve 17, as the flap valve 30 operates automatically and thus saves the interval of time that would be necessary if any other type of valve was provided to control the Y extension passages.

In case of emergency, such as the bursting of the hose line 3, the valve 17 may readily be shifted to close off the inlet throat 15.

By reference to Figures 3 and 6 of the drawings it will be obvious that the use of the rotary valve in applicant's structure enables him to close either of the ports 15, 32 or 24 as the case may be. Sometimes it happens that dirt will get under the flap valve 29 when in the position shown in Figure 4. When that occurs a back leakage or circuit of water flow from 32 through 27, through 24 back to 32 may occur, thereby reducing the efficiency of the apparatus. When the fireman finds that condition existing all he needs to do is to turn the valve 18 to close the port 24 and that will hold the pressure temporarily.

From the foregoing description, taken in connection with the accompanying drawing, it is thought that the novel details of construction, the manner of use and the advantages of my invention will be readily apparent to those skilled in the art to which it relates.

What I claim is:

A connector head of the character described comprising a hollow casing having a cylindrical valve chamber and having three ports, means whereby one port may be connected with a fire plug outlet, means whereby another port may be connected with a pumper suction line, and a Y extension having a passage connected with the third port to communicate with said chamber, a passage adapted for connection with a distributing hose line, and a passage adapted for connection with a pressure line from a pumper, a flap valve in said extension automatically operable by water pressure for closing the passage from the chamber into the extension or the passage from the pressure line, and a rotary valve in said chamber for closing any one of said three ports as desired leaving the other two in communication.

CONRAD J. DIEZ.
